Y. TSUTSUI Inventor

J. P. Gove

Attorney

UNITED STATES PATENT OFFICE.

YUKINO TSUTSUI, OF SEATTLE, WASHINGTON.

HATPIN.

Application filed October 19, 1922. Serial No. 595,543.

To all whom it may concern:

Be it known that YUKINO TSUTSUI, a citizen of Japan, residing at Seattle, in the county of King and State of Washington, has invented certain new and useful Improvements in Hatpins, of which the following is a specification.

This invention relates to improvements in hat pins.

10 The principal object of the invention is to provide a hat pin which will be effective to securely holding the hat upon the head of the wearer, and which involves the use of a construction wherein there will be no outwardly protruding points.

15 A further object of the invention is to provide a hat pin of such construction that it may be permanently attached to the hat, and one which may be conveniently manipulated to secure the hat in position, or be operated whereby the hat may be readily removed.

20 The invention also comprehends improvements in the details of construction and arrangement of parts which will be hereinafter described and particularly pointed out in the claim.

In the accompanying drawings:

Fig. 1 is a perspective view of a hat showing my improved pin applied.

30 Fig. 2 is a central vertical section of the hat pin, showing the pin extended in full lines and retracted in dotted lines.

Fig. 3 is a cross section on the line 3—3 of Fig. 2.

35 Fig. 4 is a side elevation of the hat pin.

1 indicates a pin threaded at one end as at

2. The threaded end 2 engages the head 3 of an internal cylinder on sleeve 4, the latter fitting in an outer cylinder 5 extending

40 from a disc or base 6. Interposed between the disc 6 and the head 3 and encircling the pin 1, is a spring 7, the opposite ends of the spring being secured to the disc and the head. Obviously, the tension of the spring

45 is such as to normally draw the inner sleeve 4 within the outer sleeve 5.

The base or disc 6 is provided with openings 8, through which extend screws 9, which engage in threaded openings 10 formed

50 in a disc 11.

The outer cylinder 5 is provided with a longitudinal slot 13, having its forward end extended at right angles as at 14 to form a bayonet slot, and fitting in the slot is a pin 15 secured to and projecting from the inner 55 cylinder 4.

The discs 6 and 11 are provided with aligned central apertures to form a guide-way for the pin 1 as clearly shown in Fig. 2.

Assuming that a hat is to be equipped 60 with the hat pin attachment, the hat is first punctured either on one or both sides, depending upon whether or not it is desired to have a pin on one or both sides of the hat, the puncture being indicated at 16, as shown 65 in Fig. 2. The puncture may be formed with the point of the pin. Then the attachment is placed on the outside of the hat and the disc 11 is placed on the pin 1 to bear on the inner surface of the hat, and the 70 screws 9 are engaged in the openings 10 to secure the two discs to the wall 17 of the hat as shown in Figs. 2 and 4. The attachment having now been secured in place, the spring 7 tends to draw the cylinder or 75 tubular extension 4 within the tubular extension 5 in telescopic form, hence the pin 1 is normally held in extended position. To re-

move the hat from the head of the wearer, the head 3 is grasped and the cylinder or 80 tubular extension 4 is drawn outwardly, and with the pin 1 is retracted against the tension of the spring 7, and if it be desired to hold the pin in retracted position, the head 3 is given a slight turn to bring the stud 15 85 into the right angular portion 14 of the bayonet slot. This forms a locking connection and prevents the spring 7 forcing the pin outwardly to extended position.

The cylinder 5 and head 3, as well as the 90 disc 6, may be suitably ornamented and of any approved shape and of suitable material, to lend neatness to the attachment.

As previously stated, one of the attachments may be located on each side of the 95 hat if desired as shown in dotted lines in Fig. 1.

What I claim is:

A hat pin, comprising a pair of tubular telescopic members, a pin mounted in one 100

member extending through a slot formed in the other member for limiting the telescopic movement of the members and preventing disengagement thereof, a pin secured in one member extending through the other and adapted to be contained in said members in extended relation, resilient means for nor-

mally holding the members in telescoped relation to project the pin, means for holding the members in extended relation against the tension of the spring, and means for securing the other member to a hat.

In testimony whereof I affix my signature.

YUKINO TSUTSUI.
